UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed May 3, 1922. Serial No. 558,139.

To all whom it may concern:

Be it known that I, JESSE A. B. SMITH, a citizen of the United States, residing in Stamford, in the county of Fairfield and 5 State of Connecticut, have invented certain new and useful Improvements in Type-writing Machines, of which the following is a specification.

This invention relates to typewriting machines of the class in which provision is made to straighten out the work which is fed around a cylindrical platen, so that the carbon-sheets, which are interleaved between the plies of the work, may be pulled back 10 relatively to the latter, one well-known form of machine of this class being disclosed in the patent to Wernery and Smith, No. 1,132,055, dated March 16, 1915,

In a machine of the fan-fold type, such as 20 that disclosed in said patent, it is customary to type on the outside ply of a fan-fold web and concomitantly make carbon copies on the underlying plies, all of the plies advancing together through the machine and 25 being severed simultaneously. The original and carbon copies may also be made on a plurality of independent superposed webs or plies which, as in the case of a fan-fold web, are advanced through the machine together and are drawn off or severed 30 simultaneously. Usually each of the superposed webs of plies consists of a succession of similar forms which may be of considerable length although there may not be more 35 than two or three lines of typing on each form. This would result in considerable waste of space between the successive entries on an inner work-sheet or record-sheet. It is desirable, however, to have the records, 40 or carbon copies thereof, typed on numerous successive forms, closely succeed each other on the record-sheet, which may be entirely separate from the plies or webs lying outside thereof, such a record-sheet being ordinarily 45 referred to as a condensed record-sheet. This result has been effected by holding the condensed record-sheet stationary while the webs or plies outside thereof are advanced 50 in the machine at the conclusion of the typing of each form.

The main object of the present invention is to provide novel and effective means for controlling the record-sheet and associated webs or plies provided with successive forms, 55 so as to obtain in condensed form on the

record-sheet records or copies of the entries on the successive forms.

According to the present invention, provision may be made of a clamp whereby the record-sheet, passed between the platen 60 and the front paper-table or collating table, may be clamped to the back of the latter. This arrangement renders it convenient to insert the record-sheet, and, due to the position in which the record-sheet is clamped, 65 permits use to be made of a record-sheet of any desired width and placed so as to underlie any desired portion of the superposed webs having forms thereon.

Another feature consists in provision of 70 means whereby, when the collating table is in its normal position, the clamp will be ineffective to hold the record-sheet against the back of the collating table, but, upon movement of the paper-table to permit the 75 webs to be straightened beneath the platen, the clamp will be rendered effective to hold the record-sheet against movement relative to the collating table. Provision may also be made of a finger-piece whereby the 80 clamp may be rendered ineffective at will.

If the headings on the various forms are of considerable depth, it will be necessary after severing the used forms to advance the webs to bring the desired portion of the next set 85 of forms to the printing line. This would cause the record-sheet to be advanced and a gap to be left on the latter between the preceding record and the one to be made in connection with the superposed forms in 90 position to receive an entry. To avoid this unsatisfactory condition, provision is made of severing means so positioned that, when a set of used forms has been severed, the next set of superposed forms will be positioned 95 for typing thereon. This severing device, which may be in addition to the usual paper-guiding and severing knife, may be adjustable to different positions relative to the printing line, so that it may be positioned 100 readily for forms having different depths of headings.

In as much as the record-sheet is entirely separate from the superposed plies carrying the successive forms, the record-sheet may 105 be inserted while the webs and associated carbons are in the machine and, when inserted at the introductory side of the platen, will be guided around the latter by said webs and carbons to the delivery side of the 110

- platens adjacent the lower edge of the collating table. Preferably, the insertion of the record-sheet is effected when the webs are in straightened position beneath the platen.
- 5 The lower edge of the collating table, however, lies close to the platen, and it is desirable to provide means whereby the leading edge of the record-sheet will be guided between the collating table and the platen.
- 10 To this end, provision may be made of a stripper in the form of a paper-finger mounted on the back of the collating table and extending below the lower edge of the latter and having its end flared outwardly from
- 15 the axis of the platen, so that, when the record-sheet is thrust forward with the corresponding front corner in advanced position, the advanced corner will pass back of the flared end of the guiding finger and will
- 20 be stripped and guided thereby between the collating table and the stationary platen, and the stationary superposed webs and associated carbons which support the record-sheet thus stripping the latter from the webs,
- 25 so as to insure the passage of the leading edge of the record-sheet back of the guiding finger. Following the introduction of one corner of the record-sheet between the lower edge of the collating table and the platen,
- 30 further advance of the record-sheet will cause its inclined leading edge to ride over the lower edge of the collating table until the leading end of the record-sheet lies between the lower edge of the collating table
- 35 and the platen throughout its whole width. The record-sheet may then be adjusted in position both longitudinally and transversely. To assist in aligning the record-sheet, when so introduced, provision may be made
- 40 of a side gage at the rear of the collating table. Preferably the side gage at the rear of the collating table constitutes an extension of the guiding finger, thus making it convenient to apply these devices to the rear
- 45 face of the collating table or to remove them therefrom simultaneously.
- When a record-sheet is to be inserted, the collating table is preferably swung to horizontal position to permit the webs and associated carbons to be straightened beneath the platen, and the record-sheet is thrust forward from the rear and guided by means of the offset guiding finger to the rear of the collating table, the finger-piece on the back
- 50 of the collating table being depressed to permit the leading edge of the record-sheet to pass between the clamp and the rear face of the collating table. In such movement of the record-sheet its leading edge may engage
- 55 the lower end of the usual gage-bar or the usual screw by which the gage-bar is attached to the rear of the collating table. To prevent such interference with the forward movement of the record-sheet provision
- 60 may be made of means to deflect the leading

edge of the record-sheet over the end of the gage-bar and its attached screw. Preferably, said deflecting means comprises two deflectors, one on each side of the gage-bar.

Provision may also be made of side gages 70 adjustable along a bar supported by its ends on brackets attached to the carriage at its rear, the bar being slightly to the rear of the upper edge of the rear paper-table. Heretofore side gages have been mounted on the 75 usual rock-shaft forming part of the latching means for the usual swing-frame and extending across the carriage below the upper portion of the rear paper-table in such a manner that the rear paper-table practically prevents any adjustment of the side gages. It will be evident that the new arrangement renders it possible to adjust the side gages for any desired width of web.

Other features and advantages will hereinafter appear.

In the accompanying drawings,

Figure 1 is a top plan view showing my invention applied to so much of an Underwood typewriting machine as is necessary 80 for the purpose of illustration.

Figure 2 is a view similar to Figure 1, but showing the platen in displaced position and indicating the manner in which a record-sheet is introduced, so as to pass between the 85 collating table and the platen.

Figure 3 is a detail view, partly in section, showing the manner in which the finger for guiding the record-sheet between the platen and the collating table is secured to the 90 collating table.

Figure 4 is a diagrammatic view, partly in section, of the carriage and the rearward extension on which the carbon-carrier travels.

Figure 5 is a detail view showing the manner in which the adjustable knife is mounted on the platen-displacing frame.

Figure 6 is a view similar to Figure 4, but with the rearward extension of the carriage omitted, and showing the latching device for the platen-displacing frame in the releasing position and the record-sheet clamped to the back of the collating table.

Figure 7 is a view similar to Figure 6, but showing the platen displaced, the collating table being substantially horizontal.

A platen 10 is fixedly mounted on a shaft or axle 11 journaled in ends 12 and 13 of a platen-displacing frame indicated in general by 14. The ends 12 and 13 of the platen-displacing frame 14 are pivotally mounted on a rod 15 supported at its ends by ends 16 and 17 of a typewriter-carriage 18. The typewriter-carriage also includes a rear paper-table 19, and carries front and rear feed-rolls 20 and 21, respectively, to co-operate with the platen in its normal position for feeding work-sheets therearound.

To turn the platen 10, provision is made

of a stub-shaft 22 journaled in the end 16 of the carriage, and having at its inner end a gear 23 meshing with a broad pinion 24 on the rod 15. The broad pinion 24 also 5 meshes with a gear 25 at the left-hand end of the platen-axle 11, the gear 25 being of the same size as the gear 23. The platen may be rotated by rotating the stub-shaft 22 by means of a finger-wheel 26 thereon, or 10 by the usual line-spacing means, not shown. Provision may also be made, at the right end of the carriage, of a finger-wheel 27, a stub-shaft 28 and gears 29 and 30 meshing with a broad pinion 31, the arrangement of 15 these elements being substantially the same as those of the corresponding elements at the left end of the carriage.

Connected to a cross-bar 32 of the carriage 18, by means of brackets 33, is a rearward 20 extension 34 of the carriage 18, said rearward extension comprising rails 35 on which run grooved wheels 36 on the bottom of a carbon-carrier 37. The carbon-carrier 37 comprises carbon-holders or bars 38 to which 25 the rear ends of carbon-sheets 39 are attached and between which webs or work-sheets 40 are threaded.

The webs 40 and interleaved carbon-sheets 39 extend forwardly above a bar or rod 41 30 supported at the rear of the carriage 18 by means of brackets 42, and between adjustable side gages 43 mounted on the rod 41. The side gages 43 may be secured in adjusted position by any suitable means, such as screws 43^a. The webs and carbon-sheets 35 then pass over a raised portion 44 of the rear paper-table 19 and between the latter and the platen around to the delivery side of the latter. From the delivery side of the platen 40 the webs pass upwardly between the platen and the usual knife 45 to the upper surface of a collating table 46 supported on the ends 12 and 13 of the platen-displacing frame 14. The paper-table 46 is stiffened by a cross-bar 45 47 constituting in effect a part of the collating table 46, and a gage-bar 48 of the usual form is detachably secured to the cross-bar 47 by suitable means, such as a screw 49, having a knurled head. An adjustable gage 50 50 of the usual form is mounted on the gage-bar 48.

A rock-shaft 51 extends across the carriage beneath the raised portion 44 of the rear paper-table and is journaled in the ends 16 and 17 of the carriage 18. When the platen-displacing frame 14 is in its normal position, the ends 12 and 13 thereof rest on the shaft 51 and the frame 14 is held in this position by left and right-hand latches 52 and 53, 60 respectively, both fixedly mounted on the shaft 51 and co-operating with studs 52^a and 53^a, projecting inwardly from the ends 12 and 13, respectively, to hold the frame 14 in its normal position. This shaft is normally urged to swing the latches 52 and 53

to effective position by means of coiled springs 54 and 55 at the left and right ends, respectively, of the shaft 51. To release the latches, provision is made of a finger-piece 56 forming an extension of the left-hand latch 52.

Each of the webs 40 may consist of a succession of similar forms, and, upon completion of the typing on one set of superposed forms, the webs must be advanced 75 sufficiently to enable the set of used forms to be severed. It is desirable, however, to have carbon copies of the matter typed on the different sets of forms in condensed form on a single record-sheet 57. To obtain this result, the record-sheet must be held against movement while the webs are advanced to the severing position at the conclusion of the typing of each set of superposed forms.

According to the present invention, the record-sheet is clamped against movement with reference to the collating table 46, and, as herein disclosed, this is done by means of a bail 58 having arms 59 pivoted on screws 60 threaded into the ends 12 and 13 of the platen-displacing frame 14, and a cross-bar 61 having thereon friction members 62 of suitable material to co-operate with the bar 47 at the back of the collating table to grip the record-sheet 57. Springs 63 coiled about the screws 60 tend to swing the bail 58 to effective position. Each of the arms 59, at the rear of the screw 60 on which it is pivoted, curves upwardly and forwardly, and at its end is provided with a stud 64 100 projecting outwardly therefrom to lie in the path of the hook portion of the adjacent latch of the latches 52 and 53, so that, when the frame 14 is in its normal position and said latches 52 and 53 are swung to effective 105 position, the bail 58 will be swung to ineffective position to enable the record-sheet 57 to be fed by the platen. Provision may also be made of a finger-piece 65 mounted on the left-hand arm 59 whereby the clamping bail may be moved to ineffective position.

Usually the distance from the printing point to the cutting edge of the knife, in a fan-fold machine, is approximately one inch. When, therefore, the headings on the forms 115 are more than one inch in height, it is necessary to feed the forms after the preceding severing operation to bring the first printing line to the printing point. This feature is objectionable when a separate record-sheet is used to receive a condensed record, for the record-sheet will be advanced with the forms, thus leaving a blank space between the records. In order to avoid this waste of space on the record-sheet, provision 120 is made of a knife 66 adjustably mounted on the ends 12 and 13 of the platen-displacing frame 14, the usual knife being retained to perform its function of sheet-guiding. Preferably, this adjustment is obtained by 125 130

providing downward extensions 67 at each end of the knife 66, each of the extensions 67 having a slot 68 therein through which extend screws 69 threaded into the adjacent 5 end of the frame 14. It will be evident that by loosening the screws 69 the knife 66 may be moved to different positions with reference to the printing line and clamped in these positions by tightening the screws 69. 10 This arrangement avoids the necessity of feeding the webs forwardly after the severing operation, and permits the matter on successive forms to be copied on the record-sheet without leaving unnecessary spaces 15 between the copies of successive forms.

The lower edge of the collating table 46 lies very close to the platen 10, and in order to assist in guiding the leading edge of the record-sheet 57, inserted from the rear between the carbons 39 and webs 40 and the platen, 20 between the collating table 46 and the platen 10, provision is made of a guiding finger 70. This finger is secured to the rear face of the collating table at the left- 25 hand of the latter and at the end of the platen 10. As shown in Figure 3, the finger 70, which is secured to the cross-bar 47 by means of a screw 71 having a knurled head, is flared outwardly at its lower end, and at 30 its other end there is a support 72 for a side gage 73 extending around the rear edge of the collating table toward the front thereof.

When a record-sheet 57 is to be inserted, the finger-piece 56 is swung to the rear to 35 release the platen-displacing frame 14, and the latter is swung forwardly around the rod 15 until the collating table rests upon an abutment 74 on the front rail 75 of the carriage 18. Preferably, the abutment 74 is of 40 yielding material such as rubber. It is to be understood that at this time the webs 40 are in proper position for starting typing on a new form and the carbons 39 are in retracted position. At this time the webs 40 and the carbons 39 will be held in proper 45 position relative to the collating table by means of the usual knife 45 and the adjustable knife 66. When, therefore, a record-sheet is inserted at the rear of the platen 50 between the webs 40 and the carbon-sheets 39 on one hand and the platen 10 on the other, as indicated in Figures 2 and 7, the left-hand forward corner of the sheet will be directed above the flared end of the finger 55 70, and will be guided thereby between the collating table 46 and the platen 10. As shown in Figure 2, the record-sheet is thrust forward with its leading edge in inclined position, and it will be evident that, after 60 the left forward corner has been introduced between the collating table 46 and the platen, further movement of the record-sheet will cause the inclined leading edge of the record-sheet to ride over the lower edge of the 65 collating table and pass between the latter

and the platen. The record-sheet may be straightened in the machine and gaged by the side gage 73 carried by the finger 70. In this gaging operation use may also be made of the adjustable gages 43 at the rear 70 of the carriage 18.

When the collating table is in the position shown in Figure 7, the clamping bail 58 will be in effective position. It is desirable, however, that the record-sheet 57, as it is guided 75 between the collating table 46 and the platen, be permitted to pass along the rear face of said collating table. To permit such action, the finger-piece 65 may be depressed to shift the clamping bail 58 to ineffective position, 80 further movement of the record-sheet, Figure 7, serving to move the latter between the clamping bail 58 and the cross-bar 47 at the rear of the collating table. It will be seen that, as the finger 70 is mounted on 85 the rear face of the cross-bar 47, the leading edge of the record-sheet will be guided to the rear of the cross-bar. When the record-sheet is properly adjusted, the finger-piece 65 may be released to permit the clamping bail 58 to press the record-sheet against the collating table and hold it fixed relatively thereto. The swing frame 14 may then be 90 swung to its normal position and there held by means of the latches 52, and 53, the latter, 95 in their movement to effective position, releasing the record-sheet 57 so that it may be fed with the webs 40 upon line-space movement of the platen. After the insertion of the record-sheet, as just explained, and upon 100 the return of the platen to its normal position, typing may be effected on the properly positioned set of superposed forms in the usual manner, and, upon completion of such typing, the displacing frame 14 may be swung 105 forwardly to its Figure 7 position, the clamping bail 58 being made effective automatically by the releasing of the frame 14 by the latches 52 and 53. The webs 40 may then be drawn forwardly and gaged by means of 110 the gage 50, and the carbon-sheets 39 restored to their rearward position by means of the carbon-carrier 37. The platen may then be restored to its normal position and the used forms severed over knife 66, this 115 operation being repeated for each set of superposed forms.

When a separate record-sheet is used in the fan-fold machine, the upper carbon 39 will not be guided from the platen over the 120 lower edge of the collating table 46, inasmuch as the record-sheet passes back of the collating table. This may cause trouble as a result of the engagement of the leading edge of the upper carbon-sheet with the lower edge of the collating table 46, a condition which would result in damage to the carbon-sheet. To obviate this trouble, the upper carbon 39 may be made longer than 125 the others and of sufficient length to extend 130

over the lower part of the collating table 46 when the carbon-carrier 37 is in its rearward position. This arrangement will insure proper feeding of the upper carbon 39 over the collating table 46 when advanced by the platen.

When the record-sheet 57 is moved past the bar 61 of the clamping bail, the forward edge of the record-sheet tends to engage and 10 to be obstructed by the screw 49 by which the gage-bar 48 is secured to the collating table 46. To avoid this difficulty, provision has been made of suitable deflectors 76 mounted on the cross-bar 47 on opposite 15 sides of the gage-bar 48.

Variations may be resorted to within the scope of the invention, and portions of the improvements may be used without others.

Having thus described my invention, I 20 claim:

1. In a typewriting machine, the combination with a platen, of means for displacing said platen bodily to permit work-sheets and carbons thereon to be straightened beneath the same, said displacing means comprising a swing-frame and a collating table thereon and between which and the platen a record-sheet passes, a clamp mounted upon 25 said swing frame to hold said record-sheet 30 against the back of the collating table, and controlling means for the clamp to render said clamp ineffective when the swing-frame is in normal position and effective when the swing-frame is displaced.

2. In a typewriting machine, the combination with a platen, of means for displacing said platen bodily to permit work-sheets and carbons thereon to be straightened beneath the same, said displacing means comprising a swing-frame and a collating table thereon and between which and the platen a record-sheet passes, and a clamping device to hold said record-sheet against the back of the collating table, said device comprising a bail having arms pivoted on the 40 ends of the swing-frame and a cross-bar having friction material thereon to co-operate with the back of the collating table.

3. In a typewriting machine, the combination with a platen, of means for displacing said platen bodily to permit work-sheets and carbons thereon to be straightened beneath the same, said displacing means comprising a swing-frame and a collating table 55 thereon and between which and the platen a record-sheet passes, a clamp mounted upon the swing-frame to hold said record-sheet against the back of the collating table, and a finger-piece mounted upon the swing-frame for rendering said clamp ineffective 60 when the swing-frame is displaced.

4. In a typewriting machine, the combination with a platen, of a paper-table at the delivery side of the platen to receive a plurality of superposed work-sheets and carbons

extending past the platen, said table having its lower edge close to the platen, and stripping means for engaging at one side edge a work-sheet, thrust from the rear between the stationary work-sheets and carbons and the platen, before it reaches the lower edge of the table, and stripping it from said work-sheets and guiding it between the lower edge of the table and the stationary platen, said stripping means lying between the platen and the table and extending behind the latter.

5. In a typewriting machine, the combination with a platen, of a paper-table at the delivery side of the platen to receive a plurality of superposed work-sheets and carbons extending past the platen, said table having its lower edge close to the platen, and a stripping device at one end of the platen to strip and guide the leading corner 80 of a record-sheet, thrust from the rear between the stationary work-sheets and the stationary platen with its leading edge inclined, between the table and the platen to insure the passage of the remainder of the 85 inclined leading edge of the record-sheet back of the table, said stripping device lying between the platen and the table and extending behind the latter.

6. In a typewriting machine, the combination with a platen, of a collating table at the delivery side of the platen to receive a plurality of superposed work-sheets and carbons extending past the platen, said collating table having its lower edge close to the platen, and a finger having a flared end and extending beyond the lower edge of the table whereby a record-sheet thrust, with the corner adjacent the finger in advance, from the rear between the platen and the work-sheets, 90 will be guided by the latter back of said finger and consequently back of the collating table, the inclined leading edge of the record-sheet riding over the rear edge of the collating table until the entire leading edge 95 lies to the rear of the collating table.

7. In a typewriting machine, the combination with a platen, of a collating table at the delivery side of the platen to receive a plurality of superposed work-sheets and carbons extending past the platen, said collating table having its lower edge close to the platen, means for guiding a record-sheet, thrust from the rear between said work-sheets and carbons and the platen, between the lower edge of the collating table and the platen, to pass along the rear face of the collating table, a clamp to engage the rear face of the collating table, and a finger-piece whereby the clamp may be withdrawn from 100 said rear face to permit the record-sheet to pass between said rear face and said clamp, the clamp becoming effective when the finger-piece is released.

8. In a typewriting machine, the combi-

- nation with a platen, of a collating table at the delivery side of the platen to receive a plurality of superposed work-sheets and carbons extending past the platen, said collating table having its lower edge close to the platen, and a detachable finger having a flared end and extending beyond the lower edge of the table whereby a record-sheet thrust, with the corner adjacent the finger in advance, from the rear between the platen and the work-sheets, will be guided by the latter back of said finger and consequently back of the collating table, the inclined leading edge of the record-sheet riding over the rear edge of the collating table until the entire leading edge lies to the rear of the collating table, said finger having at the end opposite the flared end a side gage to gage the record-sheet.
9. In a typewriting machine, the combination with a platen around the lower part of which a plurality of superposed work-sheets and carbons are fed, means to retract the carbons when the work-sheets are straightened, means for displacing the platen to permit the work-sheet to be straightened thereunder and the carbons to be retracted, said displacing means comprising a swing-frame having a collating table thereon between which and the platen an inner or record-sheet is passed, and a finger projecting from the back of said collating table along one end of the platen to guide a corner of the record-sheet, thrust forward with that corner in advance, back of the collating table at that end, so that further advance of the record-sheet will cause its inclined leading edge to pass between the collating table and the platen, the record-sheet then being straightened and adjusted to the proper position.
10. In a typewriting machine, the combination with a platen around the lower part of which a plurality of superposed work-sheets and carbons are fed, means to retract the carbons when the work-sheets are straightened, means for displacing the platen to permit the work-sheets to be straightened thereunder and the carbons to be retracted, said displacing means comprising a swing-frame having a collating table thereon between which and the platen an inner or record-sheet is passed, a finger projecting from the back of said collating table along one end of the platen to guide a corner of the record-sheet, thrust forward with that corner in advance, back of the collating table at that edge, so that further advance of the record-sheet will cause its inclined leading edge to pass between the collating table and the platen, the record-sheet then being straightened and adjusted to the proper position, and means to support the superposed work-sheets and carbons when straightened under the platen, to insure the

guiding of the record-sheet to the proper side of the finger to enable the latter to be effective.

11. In a typewriting machine, the combination with a platen, of means to permit superposed work-sheets and carbons to be straightened beneath the platen to permit the carbons to be drawn to the rear, said means comprising a collating table at the delivery side of the platen and a swing-frame carrying the collating table whereby the latter may be swung to a substantially horizontal position at the level of the bottom of the platen, and a guiding finger attached to the back of the collating table at one side of the path of said work-sheets and having its free end flared to the front of the collating table, whereby, upon advancing a separate work-sheet from the rear over said superposed sheets and with its forward edge inclined to project the corner adjacent the finger over the latter and between the latter and the collating table, the entire leading edge of the separate work-sheet will be guided to the back of the collating table.

12. In a typewriting machine, the combination with a platen, of means to permit superposed work-sheets and carbons to be straightened beneath the platen to permit the carbons to be drawn to the rear, said means comprising a collating table at the delivery side of the platen and a swing-frame carrying the collating table whereby the latter may be swung to a substantially horizontal position at the level of the bottom of the platen, a guiding finger attached to the back of the collating table at one side of the path of said work-sheets and having its free end flared to the front of the collating table, whereby, upon advancing a separate work-sheet from the rear over said superposed sheets and with its forward edge inclined to project the corner adjacent the finger over the latter and between the latter and the collating table, the entire leading edge of the separate work-sheet will be guided to the back of the collating table, and a side gage at the back of said collating table whereby the separate work-sheet may be gaged after its insertion back of the collating table.

13. In a typewriting machine, the combination with a platen, of means to permit superposed work-sheets and carbons to be straightened beneath the platen to permit the carbons to be drawn to the rear, said means comprising a collating table at the delivery side of the platen and a swing-frame carrying the collating table whereby the latter may be swung to a substantially horizontal position at the level of the bottom of the platen, and a guiding finger attached to the back of the collating table at one side of the path of said work-sheets and having its free end flared to the front of the col-

lating table, whereby, upon advancing a separate work-sheet from the rear over said superposed sheets and with its leading edge inclined to project the corner adjacent the finger over the latter and between the latter and the collating table, the entire leading edge of the separate work-sheet will be guided to the back of the collating table, said collating table having a gage-bar secured to its back face and means to deflect the leading edge of the inserted work-sheet over the end of the gage-bar.

14. In a typewriting machine, in combination, a platen, feeding means co-operating therewith to feed work-sheets and interleaved carbons, means to free said work-sheets from the platen, a table at the delivery side of the platen, and a clamp on the back of the table to clamp thereto an inner work-sheet passing between the table and the platen, while the other work-sheets, when freed from the platen, are advanced with reference thereto.

15. In a typewriting machine, in combination, a platen, feeding means co-operating therewith to feed work-sheets and interleaved carbons, means to free said work-sheets from the platen, a table at the delivery side of the platen, a clamp on the back of the table to clamp thereto an inner work-sheet passing between the table and the platen, while the other work-sheets are advanced with reference thereto, and means for automatically rendering said clamp effective and ineffective.

16. In a typewriting machine, the combination with a platen and feeding means co-operative therewith to feed superposed work-sheets, of a table at the delivery side of the platen behind which the inner work-sheet passes and over which the other work-sheets pass, normally ineffective means for clamping said inner sheet to the back of the table, means for releasing the work-sheets from the platen and the feeding means to permit free adjustment of the work-sheets passing over the table, and means for causing said clamping means to become effective to hold said inner sheet when the work-sheets are released from the platen and feeding means.

17. In a typewriting machine, the combination with a platen and feeding means co-operative therewith to feed superposed work-sheets, of a table at the delivery side of the platen behind which an inner work-sheet passes and over which the other work-sheets pass, normally ineffective means for clamping said inner sheet to the back of the table, means for releasing the work-sheets from said platen and the feeding means to permit free adjustment of the work-sheets passing over the table, means for causing said clamping means to be effective to hold said inner sheet while the work-sheets are released from the platen and feeding means,

and a finger-piece for rendering said clamping means ineffective.

18. In a typewriting machine of the fan-fold type, in combination, a platen, a carriage comprising a rear paper-table having at its upper edge a horizontal portion to support webs fed from the rear and passing between the rear paper-table and the platen downwardly and around the bottom of the latter, a collating table at the delivery side of the platen, a swing-frame for displacing the platen and the collating table to positions to permit the webs to be straightened under the platen, means to latch the swing-frame in its normal position, said latching means including a shaft extending transversely of the carriage beneath said horizontal portion of the rear paper-table, a rod supported on the carriage at its rear, and side gages adjustable on said rod to gage the webs immediately before they pass over said horizontal portion of the rear paper-table.

19. In a continuous billing typewriting machine, in combination, a platen, a table at the delivery side of the platen to receive superposed webs and carbon-sheets fed around the platen, a record-sheet-guiding finger extending from the rear face of the table beyond the lower edge thereof adjacent the platen, means for displacing said platen and table to permit said superposed webs and carbon-sheets on the table to be straightened beneath the platen, and means effective, when said platen and table are in displaced position, to support the superposed webs and carbons to guide a record-sheet, inserted from the rear, above said finger to be directed thereby between the table and the platen.

20. In a continuous billing typewriting machine, in combination, a platen, a table at the delivery side of the platen to receive superposed webs and carbon-sheets fed around the platen, a record-sheet-guiding finger extending from the rear face of the table beyond the lower edge thereof adjacent the platen, means for displacing said platen and table, to permit said superposed webs and carbon-sheets on the table to be straightened beneath the platen, means effective, when said platen and table are in displaced position, to support the superposed webs and carbons to guide a record-sheet, inserted from the rear, above said finger to be directed thereby between the table and the platen, and means to clamp the record-sheet against movement while shifting said webs.

21. In a continuous billing typewriting machine, in combination, a platen, a table at the delivery side of the platen to receive superposed webs and carbon-sheets fed around the platen, a record-sheet-guiding finger extending from the rear face of the table beyond the lower edge thereof adjacent the platen, means for displacing said platen

and table to permit said superposed webs and carbon-sheets on the table to be straightened beneath the platen, means effective, when said platen and table are in displaced 5 position, to support the superposed webs and carbons to guide a record-sheet, inserted from the rear, above said finger to be directed thereby between the table and the platen, and a clamp at the rear of the table to hold 10 the record-sheet fixed with respect to the table to permit shifting of the webs relatively to the record-sheet.

22. In a continuous billing typewriting machine, in combination, a platen, a table at 15 the delivery side of the platen to receive superposed webs and carbon-sheets fed around the platen, a record-sheet-guiding finger extending from the rear face of the table beyond the lower edge thereof adjacent 20 the platen, means for displacing said platen and table to permit said superposed webs and carbon-sheets on the table to be straightened beneath the platen, means effective, when said platen and table are in displaced 25 position, to support the superposed webs and carbons to guide a record-sheet, inserted from the rear, above said finger to be directed thereby between the table and the platen, means to clamp the record-sheet 30 against the rear face of the table, and means for automatically controlling said clamping means.

23. In a continuous billing typewriting machine, in combination, a platen, a table at 35 the delivery side of the platen to receive superposed webs and carbon-sheets fed around the platen, a record-sheet-guiding finger extending from the rear face of the table beyond the lower edge thereof adjacent 40 the platen, a guide between which and the platen said webs and carbon-sheets pass in advancing from the printing line to the table, a knife extending across the table and serving also as a guide to hold the super- 45 posed webs and carbon-sheets on the table, and means to displace said platen, table, guide and knife to permit the webs and carbon-sheets to be straightened under the platen, said guide and knife serving to support the straightened webs to guide a record- 50 sheet, inserted from the rear under the platen, above the finger to be directed by the latter between the table and the platen.

24. In a typewriting machine of the fan-fold type, in combination, a platen, a collating table at the delivery side of the platen to receive superposed webs and carbon-sheets fed around the platen, a finger extending from the rear face of the collating table 55 beyond the lower edge thereof adjacent the platen, a guide between which and the platen said webs and carbon-sheets pass in advancing from the printing line to the collating table, a knife extending across the collating 60 table and serving also as a guide to hold the

superposed webs and carbon-sheets on the collating table, and means to displace said platen, collating table, guide and knife to permit the webs and carbon-sheets to be straightened under the platen, said guide 70 and knife serving to support the straightened webs, so that a record-sheet inserted from the rear under the platen will be guided by said webs and carbon-sheets above the finger to be directed by the latter between 75 the collating table and the platen, said knife being adjustable to conform to different depths of headings of forms on said superposed webs, so that when one set of superposed forms has been severed the next set 80 will be positioned to receive typing thereon.

25. In a typewriting machine, a platen, a paper-table at the delivery side of the platen, and a plurality of sheet-deflectors on one face 85 of the table.

26. In a typewriting machine, a platen, a paper-table at the delivery side of the platen, a gage-bar extending in prolongation of the paper-table, and provided with a gage projecting into the path of the sheet, and a deflector on the gage-bar to prevent obstruction of the leading edge of the work-sheet. 90

27. In a typewriting machine, a platen, and a record-sheet-guiding finger positioned outside of the planes of the ends of the 95 platen.

28. In a continuous billing typewriting machine, a platen, a table at the delivery side thereof, means to displace said table for straightening continuous work-webs and 100 interleaved carbon-sheets, passing beneath the platen, sufficiently to permit relative shifting of the work-webs and carbon-sheets, and a releasable clamp for holding a work-sheet, passing around the platen between the same and the work-webs, fixed relatively to the platen during the relative shifting of the work-webs and carbon-sheets. 105

29. In a continuous billing typewriting machine, a platen, a table at the delivery side thereof, means to displace said table for straightening continuous work-webs and interleaved carbon-sheets, passing beneath the platen, sufficiently to permit relative shifting of the work-webs and carbon-sheets, a clamp for holding a work-sheet, passing around the platen between the same and the work-webs, fixed relatively to the platen during the relative shifting of the work-webs and carbon-sheets, and controlling means for the clamp to render the same ineffective when the table is in normal position and effective when the table is displaced. 110

30. In a front-strike typewriting machine, the combination with the revoluble platen and means for effecting relative shifting between printed-form work-webs and carbon-sheets fed therewith around said platen, of a work-table at the delivery side of the 115 120 125 130

platen, a knife at said work-table whereby a typed form may be severed from the web, an adjustable leading-edge gage at said work-table for correctly locating the work-web in position for severing one form therefrom and for typing the first line upon the next form, and means for affording a broad range of adjustment of said knife up and down said table to accommodate printed forms whose headings vary substantially in depth. 10

31. In a front-strike typewriting machine, the combination with a revoluble platen and means for effecting relative shifting between printed-form work-webs and carbon-sheets fed therewith around said platen, of a work-table at the delivery side of the platen, a knife at said work-table whereby a typed form may be severed from the web, an adjustable leading-edge gage at said work-table for correctly locating the work-web in position for severing one form therefrom and for typing the first line upon the next form, mounts for the ends of said knife, 15 35

15 fed therewith around said platen, of a work-table at the delivery side of the platen, a knife at said work-table whereby a typed form may be severed from the web, an adjustable leading-edge gage at said work-table for correctly locating the work-web in position for severing one form therefrom and for typing the first line upon the next form, mounts for the ends of said knife, 20 40

20 supports upon which said mounts are set-table to a broad range of positions, to ac- 25 45

commodate printed forms whose headings vary substantially in depth.

32. In a front-strike typewriting machine, the combination with a revoluble platen and means for effecting relative shifting between printed-form work-webs and carbon-sheets fed therewith around said platen, of a work-table at the delivery side of the platen, a knife at said work-table whereby a typed form may be severed from the web, an adjustable leading-edge gage at said work-table for correctly locating the work-web in position for severing one form therefrom and for typing the first line upon the next form, mounts for the ends of said knife, 30 35

35 said mounts having slots, and means upon said table engaging said slots for permitting a broad range of adjustment of said gage, to accommodate printed forms whose headings vary substantially in depth, and for securing 40 said gage in its various positions. 45
